CLAIM

The ornamental design for an enclosure for external memory as shown and described.

DESCRIPTION

FIG. 1 is a top, front, and left perspective view of an enclosure for external memory depicting a closed state showing our new design;

FIG. 2 is a bottom, rear, and right perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof;

FIG. 8 is a rear elevational view thereof;

FIG. 9 is a top, front, and left perspective view of the enclosure for external memory in an open state and in an exemplary embodiment of use;

FIG. 10 is a top, rear, and right perspective view of the enclosure for external memory in the open state and exemplary embodiment of use of FIG. 9;

FIG. 11 is a bottom, front, and right perspective view of the enclosure for external memory in the open state and exemplary embodiment of use of FIG. 9; and,

FIG. 12 is a top, front, and left perspective view of the enclosure for external memory shown in the closed state and another exemplary embodiment of use.

The broken lines in the figures represent portions of the enclosure for external memory and an environment of use that form no part of the claimed design.
